UNITED STATES PATENT OFFICE.

CHARLES M. GREEN, OF MARBLEHEAD, MASSACHUSETTS, ASSIGNOR TO THE WALTER M. LOWNEY COMPANY, OF BOSTON, MASSACHUSETTS, A CORPORATION OF MASSACHUSETTS.

COATING-MACHINE.

1,115,426.

Specification of Letters Patent. Patented Oct. 27, 1914.

Application filed April 15, 1911. Serial No. 621,365.

To all whom it may concern:

Be it known that I, CHARLES M. GREEN, of Marblehead, in the county of Essex and State of Massachusetts, a citizen of the 5 United States, have invented a new and useful Improvement in Coating-Machines, of which the following is a specification.

My invention relates primarily to the coating of centers with chocolate or other 10 substances in the manufacture of coated 13 candy, nuts, etc.

In practice the better grades of coated 15 centers are made of a material other than the coating molded into the desired shape, after which these centers are dipped one by 20 one by hand into a bath of the chocolate or other substance, the chocolate which adheres to the center covering it and forming a more or less thick coating over it. The process 25 has been carried on by machinery, but the best grades have always been covered by hand because of a prejudice against machine-made goods. The hand-made goods have always been recognized by their irregularity of surface due to hand methods and 30 by the finishing line of chocolate or other substance over the tops where the hand leaves its last mark on the piece. This mark, sometimes called the thumb mark, because 35 usually made by the thumb, when made by hand is irregular and not uniform in all the pieces.

It is much cheaper to coat centers by machinery, but various difficulties have been 40 encountered in the process and the fact that heretofore this thumb mark if put on by machine was always regular so that every piece looked like every other piece, made it impossible to sell machine-made goods 45 alongside of hand-made goods although the materials from which they were made were identical.

My invention comprises a machine in 50 which a large number of centers are coated at once and the finishing mark is so applied that the chance of any two finished pieces being exactly alike is very slight.

My invention then consists in means for 55 handling and dipping the centers, placing them under the marking pump and cleaning the handling mechanism automatically, as well as feeding the centers to the handling mechanism and removing the finished product. While all the features are shown combined in one machine, it is evident that each

may be used under a different environment for the purpose for which it is devised.

My invention will be understood by reference to the drawings in which its various parts are constructed and combined in the best form now known to me.

Figure 1 is a side elevation of a machine embodying my invention. Fig. 2 is a similar view taken from the opposite side thereof. Fig. 3 is a plan, and Fig. 4 is a longitudinal section on line 4-4 of Fig. 3. Fig. 4^a is a detail showing the tray-delivering mechanism, and Fig. 4^b is a plan of the latch used in this and other parts of the machine. Fig. 5 is an enlarged cross section on line 5-5 of Fig. 1. Fig. 6 is an enlarged vertical section on line 6-6 of Fig. 3. Fig. 7 is a horizontal section on line 7-7 of Fig. 5. Fig. 8 is an enlarged vertical section showing the carrier in the act of lifting the 75 coated centers from the coating tank. Fig. 9 is a view in which the carrier is shown in elevation at the finishing end of the machine in engagement with the releasing cam. Fig. 10 is an enlarged cross section on line 10-10 of Fig. 1. Fig. 11 is a horizontal section on line 11-11 of Fig. 10. Fig. 12 is a top view partly in section showing the track switches. Fig. 13 is a vertical section on line 13-13 of Fig. 12. Fig. 14 is a top 85 view of the center-grippers, and Fig. 15 is a vertical section thereof.

While certain of the parts of my machine may be differently arranged or assembled under other conditions and surroundings, as 90 assembled as shown they perform the following functions: The machine as a whole feeds a tray carrying centers to be covered with chocolate or other substance to a carriage provided with automatic center grippers, each set of which drops over, grips and lifts a center from the tray. The carriage or other suitable mechanism then rises, removes the empty tray, when another full tray comes into position ready for its next 100 gripping operation and moves over the coating substance tank and down to immerse the centers in the coating, the grippers when 105 advisable to do so being rotated while in the coating so that each center will be properly covered. The carriage is then lifted from the tank and continues its travel over a steam or hot water bath, first pushing a cover over it to protect the coated centers from the moisture, then depositing the coat- 110

ed centers on a tray. Then the carriage starts back and the first backward movement pulls the filled tray under the marking device. The marking device then deposits a jet of chocolate or other substance on top of each piece by means of a pump, immediately after which the tray is pulled, by the continued backward movement of the carriage, into a cooling room or elsewhere, and an empty tray replaces it ready for the next set of pieces. During the further backward movement of the carriage the cover of the cleaning tank is pushed over the tank holding the chocolate or other coating substance, the center-grippers are dipped into and rotated in the steam or hot water bath so as to remove any of the coating substance which may have adhered to them and, passing above the coating tank, the carriage reaches its first position over the feeding trays, when the cycle of operation begins again.

Having thus briefly described the operation of my invention as its organization is shown in the drawings, I will now describe the drawings in detail.

A is a frame braced by beams A¹¹ and forming a support for the various parts. On this frame A are mounted sections A⁸, A⁹ at each end of the machine and extending a short distance along its sides, the side portions of these sections being connected on each side of the machine by recessed stationary side rails A² and A³.
30 These stationary side rails each have two depressions, the depressions in each rail A² being separated by a part A¹⁰ the top level of which on each rail is substantially the height of that of the side portions of A⁸ and A⁹ and the extremities of A², A³, and the depressions in side rail A³ being separated by a similar part A¹⁰¹. The depressions are approached at each end by inclines A⁴, A⁵, A⁶ and A⁷ as will be pointed out below.
40 Mounted on bearing supports b on the frame A is the worm shaft B carrying a cam B¹ having a return spiral groove b¹ therein. One end of this worm shaft B carries fast and loose pulleys B², B³ and the other end 45 carries a sprocket wheel B⁴ connected by a chain b² to the sprocket B¹⁵ on the shaft B⁵ also supported in the parts b.

The carriage is suspended from a truck D and comprises a platform C the ends of which slide in suitable ways or openings A¹ in the frame. One end has a projection C¹ which for convenience is angular (see Fig. 5) and carries the cam pin b³ which runs in the cam groove b¹ in the cam B¹. By the rotation of the cam the carriage is carried from one end to the other of the machine and then by reason of the return portion of the worm groove is reversed in its movement and carried back again to its starting point.

D is the truck comprising a cross piece having rollers d at each end running on rails mounted on the sides of the frame as below described. From this truck D depends by means of hangers d¹ which slide 70 easily through openings in the platform C, the carrier E in which the grippers are mounted.

F, F¹ are switch rails pivotally mounted in the frame in such manner and with such switching mechanism as will allow the carrier to dip the centers into the coating substance and then hold the fingers of the center-grippers out of the steam bath while moving in one direction and after the carriage has deposited the centers, will give the fingers on its return movement the bath which is desirable to remove from them any coating substance which may adhere to them, and then raise the carrier up to allow it to pass over the tank holding the chocolate or other coating substance. 75 80 85

There are two pairs of switch rails, one switch rail of each pair being on each side of the frame and the rails of each pair are alike, and are adjusted in the same manner, so that the description of those on one side will answer equally well for those on the other side. These switch rails F , F' , are pivoted between the stationary side rails A^2 , A^3 , the switch rails F being pivoted by the pivot a to the part A^{10} of the side rail A^2 and the switch rails F' being pivoted by the pivot a^1 to the part A^{101} of the side rail A^3 . One pair of rails F extends forward toward the feeding end of the machine and the other pair F' extends rearward toward the finishing end of the machine. Each rail F has a tail pin f extending from its short end and each rail F' a similar tail pin f' extending from its short end. Each rail F has also a lifting pin f^2 extending laterally from its long end just above and within reach of the tail pin f^1 of the adjacent rail F' , each rail F' having a corresponding lifting pin f^2 extending laterally from its long end just above and within reach of the tail pin f . As a result the depression of the long ends of either rail will lift the long end of the other rail.

In addition to the parts already named, the platform C has attached to it latch bars G which are grooved as at *g* and ride horizontally with the platform C within the sides of the frame. The upper surface of each latch bar serves to hold up either the forward or rearwardly-projecting rails according to the direction in which the carriage is moving as will now be described. 120

The switch rails F have holding pins f^4 125 and the switch rails F¹ have holding pins f^5 . The ends of these pins project into the path of the latch bars G and would engage them except for the groove g in which they lie when the rails are in depressed position. 130

The switch rail F¹ has a slot f⁶ to allow the pin f⁴ to extend through it to reach the top of the latch bar. Each latch bar has two latches g¹, g², each of which is pivoted as at 5 g³, g⁴, thereto and forms a part of the top of the groove. Each groove is conveniently shaped just below its latches to allow the pins f⁴, f⁵, to rise freely on the lifting of these rails F, F¹ from a depressed to a horizontal position. These latches g¹, g², are so placed with relation to the holding pins f⁴, f⁵, that when one pair of rails F or F¹ is lifted 10 as above described the holding pins f⁴ or f⁵ of that rail will lift the corresponding latches g¹ or g² (see Fig. 8), rising to the level of the upper surface of the latch bars and allowing the latches to close under them. When the latches fall after the holding pins 15 have passed up by them, the holding pins f⁴ or f⁵ will thereafter rest on the upper surface of the latch bars holding up said rails as the latch bars slide under them so that the truck will move on the higher level until it is delivered to the stationary rails at the 20 end of the machine, and the latch bars have passed from under the holding pins, at which time the rail will drop, this taking place near the end of the movement of the carriage in either direction. Inclines A⁴, A⁵, 25 A⁶ and A⁷ are provided to change the level of movement of the truck D as will now be described.

The path of the truck D supporting the carriage from the feeding to the delivery end 30 of the machine is first along the side sections of A⁸ onto the stationary side rails A², A³, then down the incline A⁵ onto the depression in the rails A², A³, then onto the switch rails F, by which, as above described, the switch 35 rails F¹ are lifted to a horizontal position and thereafter are held in that position by means of the holding pins f⁴ which come up through the latches g¹ and rest on the surface of the latch bars G which slide under them. The truck then runs along the incline A⁴, along A¹⁰, A¹⁰¹, and the switch rail 40 F¹ to the further end of rails A², A³, and the side section of A⁹, the switch rails F¹ being then released by the latch bars G. On its 45 return movement the truck runs from the side sections of A⁹ and the ends of rails A², A³, down the incline A⁷ onto the depression in rails A², A³, and then onto the switch rails F¹, thus lifting the switch rails F, then 50 up switch rails F¹ and the incline A⁶, over A¹⁰, along the switch rails F, which are now in horizontal position, onto the ends of the stationary rails A², A³ and the side sections of A⁸. In this latter case the holding 55 pins f³ coöperate with the latches g² as the switch rails F are lifted and hold up the switch rails F by engaging the upper surface of the latch bars G, precisely as before described with regard to the switch rails F¹. 60 The carriage comprises not only the truck 65

D, the platform C and the other parts above described, but also the carrier E carrying the center-grippers by means of which the centers are gripped, lifted from the tray, coated and deposited on the receiving tray. 70 As stated above, the carrier E is suspended from the truck D by means of hangers d¹ the lower ends of which are attached to the carrier. The carrier is pierced by a number of holes or bearings each of which carries 75 a center-gripper preferably of the kind now to be described and adapted to be turned in said bearings.

Each center-gripper as shown comprises a sleeve e having a gear e¹ at its upper end and from its lower end depend a number of finger bearings e² to each of which is pivoted at e³ a finger e⁴. These fingers are preferably made of stiff wire or sheet metal, the lower end of each finger being bent inwardly 80 and more or less sharpened as at e⁵ or otherwise shaped to coöperate with the other fingers in gripping the center. These fingers are operated in the following manner: Within the sleeve e is a plunger e⁶ having a head e⁷. Between the lower rim of these heads and the upper end of the sleeve lies a spring e⁸ the tendency of which is to hold the plunger in a raised position. The lower end of the plunger is provided with a conical cavity e⁹ closed at its lower end by a perforated plate e¹⁰ through each perforation e¹¹ of which passes the upper end of one of the fingers e⁴, this construction being such that upon the depression of the plunger the upper 90 end of the fingers lying as they do within the cavity e⁹ will be drawn together, thus separating the lower ends of the fingers, and upon the release of the plunger the upper end of the fingers will be positively forced 95 apart so that the lower ends of the fingers will approach and grip the centers which they will surround. The carrier E may be provided with any convenient number of these center-grippers, the carrier shown in 100 the drawings having seventy such grippers, the machine shown being adapted to coat seventy centers at a time.

To operate the plungers, which it will be noticed are arranged ten in a line across the 105 carrier, there are provided seven cam rods H which extend across the carrier, the number being determined in the machine shown by the number of cross rows of grippers which the carrier contains. The cam rods 110 rest on the top of the plungers e⁶ and are held against them by long friction rolls H¹ supported at each end in uprights H². Each cam rod H has a number of wedge-shaped surfaces h each narrower than the 115 diameter of the plungers and also than the width of the cam rod and each in line with and coöperating to engage with one of the plunger heads so that when the cam rods 120 are all pushed in a direction across the car- 125

rier they will depress all the plungers and cause the opening of the fingers, this taking place at such time that the carrier will descend toward the centers with the fingers open. The wedge surfaces then pass off the plungers and release them so that each set of fingers will grip its center and hold it tightly during the coating operation. This movement of the cam rods is accomplished 10 as follows: The cam rods are restrained in their movements across the carrier by springs h^1 , one end of each spring being attached to a cam rod as at h^2 and the other end to the carrier as at h^3 . The cam rods 15 must be given a slight lateral movement in order to carry the abrupt ends of the wedges which have passed the plunger heads out of registry with those heads so that they may be returned to their original position by the 20 springs h^1 . For this purpose the carrier E has slotted end pieces h^4 , h^5 , one slot in each end piece being provided for each cam rod. One surface h^6 of each slot in the end piece h^4 is shaped to coöperate with the end surface H^2 of its cam rod H. Two slide rods 25 h^8 are also provided, each sliding in bearings h^9 in the carrier E. Each is bent at one end and enlarged to form an abutment h^{10} between which and the side of the carrier is a 30 spring h^{11} held in place by centering pins h^{12} . The springs h^{11} hold the slide rod normally in extended position. Each slide rod is also grooved crosswise to receive a cam rod H, the walls of the slot being adapted 35 to engage the slide rod and move it as occasion may require. Normally, however, the slide rods are in the position shown in Fig. 7 engaging the cam rods by means of the springs h^{11} . Thus the cam rods H are controlled 40 by the springs h^1 and h^{11} . They are moved longitudinally by means of a stationary cam piece H^6 attached to one side of the frame and having an incline H^6 so that as the carrier moves to the right (see Fig. 7) 45 to receive its load the end of each cam rod in turn will ride against the incline H^6 on the cam piece H^5 and the cam rod will be gradually pushed across the carrier, thus causing its wedge-shaped surfaces each to 50 engage its own plunger e^6 , depress it and thus cause the opening of the fingers to receive the centers, the fingers being fully open when the end of the cam rod engages the surface of H^6 . During a portion of this 55 action the carrier is dropping so that the fingers will reach around the centers. The lower edge of the cam piece H^6 has a slight inward inclination H^7 which at the end of the downward movement of the carrier will 60 give the cam rods an additional endwise thrust and push the wedge surfaces off from the plungers, thus releasing them and causing the fingers to close about the centers. When the cam rods are freed the springs h^1 65 and h^{11} drag the cam rods back toward their

original position, the wedge pieces passing one side of the plungers, and when they are disengaged from the cam piece H^6 they at once resume their original position. The release of the plungers takes place when the 70 fingers are surrounding the centers and, as above stated, they immediately grip the centers and are ready to lift them as the carrier lifts, and convey them to the chocolate tank.

The vertical movement or dropping and raising of the carrier to grip the centers at the start is accomplished as follows: The side portions of the end section A⁸ are cut away at a^2 and within each cut is a forked block a^3 held in a forward position by a spring a^4 centered by a rod a^5 attached thereto, the frame being recessed to allow the rear end of the rod to retract as required. The block when in its forward position leaves an opening in the side frames, of sufficient size 85 and depth to allow the truck rollers d to fall into it and thus drop the carrier E so that the fingers e^4 may grip the centers. The worm B then changes the direction of movement of the carriage, and to lift the carrier 90 and the rollers d out of the cut a^2 a stationary inclined surface a^6 is provided between the forks of the block a^3 up which the rollers d are dragged and in their act of moving they push back the block a^3 against the force 95 of the spring a^5 riding up the inclines onto the top of the side portion of A⁸. At the other end of the machine similar elevating mechanism will be found which operates in the same way to change the level of the 100 carrier as will be described below.

J is the tank holding the chocolate or other coating substance which may be filled and kept at the proper temperature in any desirable way. I shall hereinafter call it the 105 coating tank. It is suitably supported in the frame and beyond it is a bath K suitably supplied with steam or hot water for the purpose of cleansing the fingers after they have released the coated centers. I prefer to provide a cover K¹ which is used to cover these tanks alternately, being moved from one to the other preferably by the advancing carriage. For this purpose the cover K¹ has standards k , k^1 , adapted to 110 engage springs arms which project from the front and rear of the carriage. As shown there are four of these standards two k near one end of the cover and two k^1 near the other end of the cover and there are four 115 arms carried by the carriage. Each arm as shown comprises a part k^2 projecting from the platform C and having a leaf spring k^3 extending from it and carrying a lug k^4 at its end. As the carriage advances the lugs 120 k^4 on the advancing arms strike the standards k and push the cover K¹ until it strikes the stop K² near the further end of the machine, thus exposing the tank in advance 125 of the travel of the carriage over it and cov- 130

ering the steam bath. The springs k^3 allow the lugs to spring over the standards when the cover has reached the stop without hindering the forward movement of the carriage. On its return movement the lugs k^4 on what were the rear arms and are now the advancing arms in like manner engage the standards k^1 and push the cover K^1 over the coating tank, thus exposing the bath, 10 the cover eventually engaging the wall K^2 which acts as a stop as before.

The truck in its movement over the side frames runs down the inclines A^5 onto depressions in the side rails A^2 , A^3 , thus bringing the grippers to such level that the centers will be immersed in the coating substance in the tank. To insure their being thoroughly coated the gears e^1 on the center-grippers in each cross line are in mesh and 20 in mesh with one gear in each line is a rack E^1 of considerable length. Upon the side frames are stops E^2 located to engage one end of the rack when the centers are being covered and hold it from moving, so that 25 the center-gripper gears, engaged by it, being carried by the moving carriage will be turned. The racks are disengaged from the stops by the lifting of the carriage from the coating tank or bath as the case may be. In 30 like manner the rack will be held stationary while the grippers are being moved through the bath on the return movement causing an excessive rotary movement of the grippers.

The truck D , with the carrier E depending from it, is moved up the incline A^4 over the part A^{10} , A^{101} , of the stationary rails A^2 , A^3 and onto the switch rails F^1 again after the coating process, and is carried on a level to the cuts a^2 at the end of the carriage movement when the carrier drops and the fingers are opened to release the covered centers onto a tray suitably placed to receive them. These cuts are in all respects like the corresponding cuts a^2 at the other end of the 45 machine and are provided with similar blocks a^3 , springs a^5 and inclines a^6 , reversed in direction, however, in order to operate on the return movement of the truck D . To open the fingers I have provided a slide plate 50 L mounted on a bracket l attached to the side frames to slide horizontally and at a sufficient height and with a proper surface to engage the ends of all the cam rods H . The shaft B^5 carries one member of a clutch 55 the other member of which is carried by a shaft B^{51} supported on the frame. On the shaft B^{51} is a cam B^6 adapted to engage and move this slide at the proper time against the ends of the cam rods to push them laterally so that they will depress the plungers as before and cause the fingers to release the coated pieces dropping them upon a tray and holding the fingers open until the center-grippers have passed above the 60 coated pieces. The slide plate L is held

against the cam B^6 by the spring l^1 . The clutch member on the end of B^{51} is brought into engagement with the clutch member on shaft B^5 by the cam B^6 and shaft B^5 . This cam, by means of a cam rod B^9 which carries a shipper fork B^{10} , engaging said clutch member on shaft B^{51} , causes said clutch member to slide along the shaft B^{51} into or out of engagement with the other clutch member as occasion may require. This 70 mechanism will be recognized as a well-known mechanical expedient and therefore need not be further described. The carriage having deposited its load immediately starts back up the incline a^6 and down the inclines A^7 so that the center-grippers are washed in the bath, being rotated as before by the rack E^1 this time engaging the stops E^3 , the cover being moved in advance of the carriage onto the top of the coating tank. The carriage then moves up the inclines A^6 over the stationary rails at A^{10} , A^{101} , and onto the switch rails F^1 which are held in horizontal position, and onto the stationary rails A^2 , A^3 and along A^8 until it reaches the cut a^2 into which it drops and the entire operation is 75 repeated.

In addition to the coating process, my machine provides means for finishing the coating by applying thereto a small jet of the coating substance leaving an irregular line on the top of each piece like that resulting from hand work. For this purpose I provide a pump of a size corresponding to the size of the carrier E . This pump consists of a casing M having a perforated bottom, the casing being mounted by suitable means between the side frames of the machine. Within the casing is a plunger M^1 having a suitable plunger rod M^2 connected 100 with a lever M^3 supported on a standard M^4 and connected by means of an eccentric rod M^5 operated by an eccentric M^6 on the shaft B^{51} . A suitable stuffing box M^7 is provided for the plunger rod M^2 in the top or cover 105 of the casing. The bottom M^8 of the casing is perforated with a number of holes corresponding to the number of center-grippers in the carrier E . These holes are connected to an equal number of similarly placed holes 110 by pieces of flexible tubing m , in a plate m^1 so placed that when the carriage has pulled the tray of coated pieces under it, each hole will be over one of the coated pieces on the tray. This plate m^1 has a slide m^{100} at each 115 end each of which slides in bars m^2 set in corresponding openings in the side frames. In addition there is a slide m^{20} in each slotted extension m^{100} and through a slot m^4 in each slide m^{20} passes a pin m^3 , m^{31} , the 120 ends of which pins are confined in the bearings. The plate m^1 is capable therefore of an irregular movement, being not only movable directly across the machine but also lengthwise of the machine, this movement 125 130

being restrained somewhat, however, by the pins m^3 , m^{31} and the slides m^{20} . The pin m^{31} is longer than the pin m^3 passing not only through the cut-off m^{14} but also up 5 through a slot in the cam rod m^6 and serving as a pivot for the bar m^9 . This plate m^1 is reciprocated by means of a peripheral cam m^5 on the shaft B^{51} and a cam rod m^6 which is slotted as at m^7 , so as not to interfere 10 with the tubes m , passes over, and is attached to, a post m^8 mounted in the middle of the plate m^1 . In addition, an oscillating bar m^9 slotted as at m^{10} loosely engages the post m^8 , being pivotally connected to the 15 plate m^1 by the pin m^{31} , its outer end being operated by face cams m^{11} . Springs m^{12} hold the plate in normal position against the cam m^5 . As the cam m^5 revolves therefore the plate m^1 has a reciprocating movement given it by the peripheral surface of the cam m^5 and an irregular lateral movement given it by the face cams m^{11} so that when the coating substance is being forced through the tubes m it is fed upon the coated 20 centers below. m^{13} are springs which resist the action of the face cams m^{11} . m^{14} is a cut off plate which also slides in one side of said frame and in ways on the under side of said plate m^1 . It is perforated and is given a 25 movement by means of a cam m^{16} on the shaft B^{51} so that at the proper time it will cut off the flow of coating substance through the tubes m and plate m^1 . It is provided with openings adapted to register at proper 30 times with the perforations in the plate m^1 . m^{16} is a spring attached at one end to a bracket m^{17} and at the other end to the cut off to hold the end of the cut off against the cam. 35

40 In order to supply material to the casing beneath the plunger I prefer to provide a tube J^1 which connects the chamber beneath the plunger with the coating tank J , but this may be supplied from any other convenient 45 source. It will be seen that upon the up stroke of the plunger M^1 (the cut off being closed) the chamber M^{14} beneath it will be filled with the coating substance through the pipe J^1 and upon its down stroke the coating substance will be forced out through the 50 tubes m . As the plate m^1 in which the ends of these tubes are fastened is given an irregular movement it will be seen that the jet from these tubes will furnish an irregular 55 finish to the drops below them. It is of course apparent that the pipe J^1 should be provided with a check valve so that on the down stroke of the pump, if the passages through the cut off from the tubes m are 60 open, the coating material will be forced out through them, whereas if the cut off is closed the coating material will be forced back again into the coating tank.

I have described above the various instrumentalities which are shown in the draw-

ings as an embodiment of my invention so far as it relates to the coating and marking mechanism. There remains to be described the mechanism whereby the centers are fed to the center-grippers and after the coating process is finished the product is automatically removed.

As shown the feeding mechanism is operated by the carriage as follows: N , N^1 are trays each of which is provided with recesses n in number equal to the number of center-grippers in the carriage and registering therewith when the trays are in delivery position. As shown these trays are arranged in two stacks, one the stack comprising the filled trays N and the other the stack comprising the empty trays N^1 . Each stack of trays is arranged in vertical runways N^2 , N^3 , by which they are guided in their vertical movements and they are supported in the following manner:—Upon the side bars A^{11} is a platform N^4 which carries eight rectangular uprights N^5 , N^6 , of proper size to receive the trays and center them. N^7 , N^8 , are floorings each carrying two cleats N^9 . In starting up the machine a number of filled trays N are placed upon the cleats N^9 of flooring N^7 and under the lower tray is passed a plate n^1 forked at each end. Two stirrups n^2 are provided one on each side of the machine each supported by a cord n^3 running over pulleys n^4 as shown and weighted by weights n^5 , each stirrup being adapted to be placed under one end of the plate n^1 , its cord passing up through the fork. By this means the trays are raised and the upper tray bears against stops n^6 which limit the upward movement of the tray, the trays having walls N^{10} the upper edges of which in the top trays engage the stops n^6 and in the lower trays serve to support the next upper tray in the pile as the case may be. The stack N^1 comprises the empty trays, except that the top tray of the stack is filled (see Fig. 6), having been previously moved over from stack N and placed under the carriage E . The removal of the top tray of stack N allows the weight n^5 to lift the stack N so that what was its second tray from the top now becomes the first tray. The tray-feeding operation comprises the sliding of the top tray of the stack N onto stack N^1 after which the other trays in stack N are lifted the thickness of one tray so as to present a fresh filled tray at the top of the stack and the empty trays in stack N^1 are previously correspondingly depressed to make room for the full one from stack N . The stack N^1 is held up against its stops n^6 by a notched plate n^7 , stirrups n^{71} and cords n^8 running over pulleys n^9 and weighted by weights n^{10} exactly like stack N .

The necessary movements are given to the trays in the following manner by means

of the platform C: P is a slide running in partially covered ways p within two arms P^1 extending from the section A^8 , the cover being indicated at p^{10} . This slide is slotted to receive one end of a slotted rocker arm P^2 which is connected thereto by a pin p^1 . The other end of the rocker arm is mounted on a rock shaft P^3 the ends of which are mounted in bearings P^4 supported on the side rails of the frame. Q are levers also pivoted to the side bars of the frame at q . The rock shaft P^3 carries cams P^5 at each end, on each of which rests one end of the levers Q. The other end of each lever Q is forked and is pivoted by a pin q^1 to a block Q^1 adapted to slide vertically and carrying at its lower end a cam lug Q^2 pivoted to swing in and out from the path of the trays (see Fig. 5.) A forward movement is given to the slide P by means of the latch p^2 which is pivoted at p^{21} in the loop p^3 pivotally attached at p^{31} to the slide P (see Figs. 4^b and 6) and moving in the covered ways p . The construction of this type of latch is shown in Fig. 4^b. This latch lies in the position shown in Fig. 6 engaged by the platform C while the loop p^3 is held down by the covered portion p^{10} of the ways, but when the slide P has advanced so far that the loop p^3 has moved from under the cover p^{10} the continued engagement of the latch p^2 with the moving platform causes the loop p^3 to turn up about its pivot so that the platform C rides away from under it. A stop p^4 depending from the slide P in rear of the platform is engaged by the platform on its return movement to return the slide P and the parts operated thereby to their original position. Connected with the platform C to move with it are rearwardly-extending arms R running during the operative portion of its travel in a covered way, the same as P, each having near its end similar latches r, the level of these arms and latches being such that the latches will engage the top tray of the stack N at the proper moment and slide it onto the top of the stack N^1 and then release it, the cover of the ways extending to the point where the latches should release the tray. As the platform C moves forward it carries the slide P which in turn moves the rocker arm P^2 and turns the rock shaft P^3 and cams P^5 through an arc of say 90°, thus depressing the block Q^1 by means of the lever Q and with it the cam lug Q^2 which depresses the top tray of the stack N^1 from which the centers have just been removed, the entire stack yielding as it is only held up by the weighted cords and stirrups. The parts are so proportioned that when the empty top tray of stack N^1 has been sufficiently depressed, the full top tray of stack N is engaged by the latches r and is drawn by the still moving arms R onto the top of

stack N^1 above the cam surface of cam lugs Q^2 , the other trays in stack N being lifted by the weighted cords as soon as the top one has been removed. By the time the slide P has ceased its movement and become disengaged from the platform C the top tray of stack N has been placed on stack N^1 and on its return movement the platform C replaces the slide P, thus releasing the cam lugs Q^2 which are moved upward into their original position, the cam surface causing them to slide around the edges of the tray, the frame being slotted to allow them so to do.

I prefer to provide a double set of plates, 30 weighted cords and stirrups for each stack in order that no stoppage of the machine will be necessary when new filled trays are to be added or empty trays are removed. These lifting elements are shown in the 35 drawing lettered, the stirrups, n^{12} , cords, n^{13} , pulleys, n^{14} , and weights, n^{15} . When the filled trays are nearly exhausted a number of filled trays are placed on the cleats N^{10} , a plate put under them and the stirrups 40 n^{12} adjusted in place. The weights n^{15} then lift these new trays into place under those above them after which the stirrups n^2 are disengaged from plate n^1 and the plate withdrawn so that the stack is now held up by 45 the weights n^{15} . Later, when necessary, new trays are placed on the cleats and the weights n^5 used to move them and hold them in place as before. By a similar use of the stirrups n^{17} , cords n^{18} , pulleys n^{19} and 50 weights n^{20} the superfluous trays from stack N^1 may be removed. When the carriage has reached the other end of the machine carrying with it the covered centers the product is dropped upon a tray and is finished as 55 above described. The trays at this end are lifted in a way similar to the way in which the trays are lifted at the other end. In this case, however, only a single stack S of trays are needed as the filled trays carrying the finished product are moved horizontally away from the machine as will now be described, to be cooled and packed. The stack S is supported, centered and lifted in the same way as the stack N and therefore 60 this mechanism need not be described except to state that S^1 is the plate supporting the stack S, the stirrups in use are S^2 , their cords S^3 , their pulleys S^4 , their weights S^5 , and S^{12} the spare stirrups, S^{13} the spare 65 cords, S^{14} the spare pulleys and S^{15} the spare weights.

In Fig. 9 the carriage is shown depositing the product upon the top tray S^6 of the stack S. The platform C has two forwardly-extending arms T each of which has a latch t both of the same character as that above described, and shown in detail in Fig. 4^b. These arms run in the grooves A^1 in which the platform C runs, which grooves 70

are provided with covers T^{51} at the rear of the machine to hold the latches in operative engagement with the slides T^6 . T^1 are slides one in each side of the machine and moving in ways T^2 , each carrying an arm which has a spring hook t^1 at its further end adapted to engage the top tray S^6 in the stack S . T^6 are also slides mounted to slide lengthwise of the machine on a higher level than slides T^1 and within reach of the latches on the arms T . Each slide T^1 is connected with the slide T^6 on the same side of the machine by means of a cord t^2 running over a pulley T^3 at the rear of the machine. A weight T^4 is also connected to each slide T^1 by a cord running over a pulley T^6 so that the slides T^1 are held normally in a forward position and at its next rearward position the hooks t^1 will engage the top tray S^6 of the stack S and push it from the top of the stack onto the frame under the pump, at the same time pushing the previously moved trays S^7 out of the way.

The operation of this part of my invention is as follows: As the carriage reaches its rearward position over the stack S and discharges the dipped centers on the top tray S^6 , the latches t pass over the slides T^6 engaging therewith so that upon the return movement of the carriage the slides T^6 will be moved by it. By this movement of the slides T^6 the hooks t^1 will be moved rearward engaging the top tray and pulling it under the pump. When the tray has reached that position each latch t will release its slide T^6 owing to a gap at that point in the cover T^{51} of the way A^1 and the weights T^4 will pull the slides back to their original position, suitable stops being provided to limit their movement.

The general operation of the machine will be sufficiently understood from what has been said above without further explanation—and other applications of the various elements described may be made without departing from the spirit of my invention. The centers may be jarred or otherwise treated after being coated, if thought best, to shake off any superfluous coating. Devices for this purpose are well known and therefore are not shown or described in this specification, as their use is not always necessary. Moreover, in some cases the cleansing tank will not be found necessary and may be omitted and the pump mechanism is only necessary when it is desired to give the finish referred to to the coated product.

What I claim as my invention is:—

1. A coating machine comprising a carriage having individual center grippers, means for presenting centers to said grippers, means for causing said grippers to grip said centers, means for giving said carriage a vertical movement toward and from said center-presenting means, a tank, and means

for moving said carriage horizontally to said tank and means for giving said carriage a vertical movement to dip said centers in the contents of said tank.

2. A coating machine comprising a carriage having individual center-grippers, means for presenting centers to said grippers, means for causing said grippers to grip said centers, means for giving said carriage a vertical movement toward and from said center-presenting means, a tank, and means for moving said carriage horizontally to said tank, means for giving said carriage a vertical movement to lower said centers into said tank and withdraw them therefrom, and means for causing said grippers to release said centers. 70 75 80

3. A coating machine comprising a carriage having individual center grippers, means for presenting centers to said grippers, means for causing said grippers to grip said centers, means for giving said carriage a vertical movement toward and from said center-presenting means, a tank, and means for moving said carriage horizontally to said tank, means for giving said carriage a vertical movement to lower said centers into said tank, means for turning said centers while in said tank and for withdrawing them therefrom, and means for 85 90 95 causing said grippers to release said centers.

4. A coating machine comprising a carriage having individual center grippers, means for presenting centers to said grippers, means for causing said grippers to grip said centers, means for giving said carriage a vertical movement toward and from said center-presenting means, a tank, and means for moving said carriage thereto, and means for dipping said centers in said tank. 100 105

5. A coating machine comprising a carriage having individual center-grippers, means for presenting centers to said grippers, means for causing said grippers to grip the centers, a tank, means for moving said carriage thereto, means for causing said grippers to dip the centers therein, means for causing said grippers to release the centers, and means for applying a finish to the coated centers operable after they have been 110 115 released.

6. In a coating machine, a series of individual center-grippers each adapted to grip and release a center, a tank, means for conveying said center grippers over said tank, 120 means for causing said grippers to dip said centers therein and means for conveying said grippers from said tank over a receiver for said centers, and means for releasing said centers. 125

7. In a coating machine, a series of individual center-grippers each adapted to grip and release a center, a center presenting means, means for causing each gripper to grip and release a center, a tank, means for 130

conveying said grippers to said tank and for causing said grippers to dip said centers therein, and means for conveying said grippers away from said tank and means for causing each gripper to release its center, a receiving means for said centers.

8. In a coating machine, a series of individual center grippers each adapted to grip and release a center, a center-presenting means, means for causing each gripper to grip and release a center, a tank, means for conveying said grippers to said tank and for causing said grippers to grip the centers therein, and means for conveying said grippers away from said tank, and means for causing each gripper to release its center, a receiving means to receive said centers when released, means for ornamenting said centers, and means for conveying said receiving means under said ornamenting means.

9. In a coating machine, the series of individual center grippers, means for supporting them, and means for causing each to open and close upon a center, each gripper comprising a series of fingers, each finger being inclined outwardly to pass around a center and bent inwardly at its tip to hold said center by a single point, in combination with means to support said centers while they are being engaged by said grippers.

10. In a coating machine, a carrier, a series of center grippers located thereon, means for operating said center grippers to grip centers, means for moving said carrier vertically operable after said centers have been gripped, means for moving said carrier horizontally, a tank, means for lowering said carrier over said tank whereby said centers will be dipped therein, means for lifting said carrier to withdraw said centers from said tank, means for moving said carrier horizontally from over said tank to a place of deposit for said centers, and means for operating said center grippers to release said centers.

11. In a coating machine, in combination with means for supporting centers and means for bringing a center gripper into operative relation thereto, a center gripper comprising a sleeve, fingers pivotally mounted on said sleeve between their ends, said fingers being adapted to be opened and closed toward a center, and means for operating said fingers comprising a chambered plunger movable in said sleeve and inclosing the ends of said fingers and adapted to engage and move them while traveling in one direction, and a perforated plate closing the chamber in said plunger, the ends of said fingers passing through the perforations in said plate and adapted to engage them through the movement of said plunger, whereby said fingers will be moved positively by the movement of the plunger

in either direction with relation to said sleeve.

12. In a coating machine, a carrier, a series of center-grippers mounted thereon each comprising a spring-controlled plunger, fingers pivotally supported below said plunger, said plunger being chambered, the upper ends of said fingers lying within the chamber in said plunger, and means for moving all of said plungers simultaneously to operate said fingers, one element of said means being also mounted on said carrier.

13. In a coating machine, a carrier, a series of center-grippers mounted thereon each comprising a spring-controlled plunger, and means for operating said plungers, comprising rods also located on said carrier and having a number of cam surfaces each located to engage one of said plungers, means for moving said carrier and means for moving said rods during the movement of said carrier.

14. In a coating machine, a carrier and means for moving it, a series of center-grippers mounted on said carrier each comprising a spring-controlled plunger, and means for operating said plungers comprising rods each having a number of cam surfaces each located to engage one of said plungers, positive means for moving said rods operable by the movement of said carrier, cam surfaces to direct the movements of said rods, and means for holding said rods against said cam surfaces.

15. In a coating machine, a carrier, a tray and a tank, and means for moving said carrier horizontally from said tray to said tank, a series of center grippers mounted on said carrier and adapted to grip centers mounted on said tray, each center gripper comprising a plunger, means for moving said carrier toward and from said tray, whereby said center grippers will secure their centers, and means for moving said gripper toward and from said tank, and means adapted to engage said plungers while said centers are in said tank to cause the rotation of said plungers and said centers.

16. In combination, a carrier having center grippers, a tray, means for giving said carrier a movement toward and from said tray and means for simultaneously operating said center grippers, whereby upon the upward movement of the carrier said grippers will lift centers from said tray, means for giving said carrier a horizontal reciprocating movement from a position over said tray to a position over a second tray, and means for causing said center grippers to place centers on said second tray, and means for coating said centers located intermediate said trays.

17. In a coating machine, a carrier, means carried by said carrier to grip centers automatically, a tank, and means adapted to

give said carrier a vertically reciprocating movement to dip said centers therein, means for giving said carrier a horizontal movement after said gripping movement, means 5 to receive said centers and means whereby said carrier will deposit said dipped centers upon said receiving means.

18. In a coating machine, a carrier, means carried by said carrier to grip centers automatically, means for giving said carrier a vertically reciprocating movement into reach 10 of said centers to grip them, a tank, means for conveying said carrier to said tank and for causing said carrier to dip the centers 15 therein, means for lifting said centers from said tank and conveying said carrier to a place of deposit, and means for depositing the dipped centers thereon.

19. In combination, a truck and means 20 for moving it horizontally, a carrier depending from said truck, rails for said truck, each rail being provided with a cut to give said truck and carrier a sudden vertical drop at one end of its horizontal movement, and 25 an inclined surface adapted to allow the return of said truck to the upper level of said rails.

20. In combination, a truck and means for moving it horizontally, a carrier depending 30 from said truck, rails for said truck each rail having a cut therein to give the truck and carrier a sudden drop at the end of its horizontal movement and an incline to allow it on its return horizontal movement to ride 35 up to its normal level, in combination with a spring-controlled block forming normally one edge of said cut and adapted to be moved by said truck on said return movement to expose said incline to the action of said truck 40 in climbing to its normal level.

21. In combination, with a tank for holding the coating substance and a cleaning tank located in line therewith, a carriage having center-grippers, means for 45 causing the grippers while moving in one direction to enter one of said tanks only and when moving in the other direction to enter the other of said tanks only, comprising two pairs of switch rails and means connecting 50 them whereby the depression of one pair of rails will cause the lifting of the other pair of rails, and means for leading said carriage onto and off from said switch rails.

22. In combination, a carriage having 55 center-grippers, rails to support said carriage, said rails having depressions and two pairs of switch rails located in said depressions and adapted to lift said carriage therefrom, means connecting said 60 switch rails whereby the depression of one pair of switch rails will cause the raising of the other pair of switch rails, and means for supporting the switch rails so raised.

23. In a coating machine, in combination

with a tank for holding a coating substance 65 and a cleaning tank located in line therewith, a carrier and means for moving it over said tanks, and a cover adapted to cover one of said tanks, and means located on said carrier whereby said cover will be pushed 70 from one tank to the other.

24. In a coating machine, in combination with a tank for holding a coating substance and a cleaning tank located in line therewith, a horizontally - reciprocating carriage 75 having center-grippers and means whereby said grippers are dipped into said coating tank and pushed over said cleaning tank while moving in one direction and are dipped in said cleaning tank and passed over 80 said coating tank while moving in the other direction.

25. In a coating machine, a carrier, center-grippers located thereon, means comprising cam rods located on said carrier to operate said center-grippers, and means for operating said cam rods comprising a plate adapted to engage said cam rods and means for operating said plate periodically comprising a worm shaft, a cam located thereon 85 to engage said plate and means for periodically operating said worm shaft.

26. In a machine of the kind described, a finishing mechanism comprising a pump, a 95 perforated plate, a series of tubes connecting said pump with the perforations in said plate, and means for giving said plate an irregular horizontal movement, said means comprising a face cam adapted to give said plate a reciprocating movement, a spring 100 adapted to hold said plate against said cam, and cam surfaces adapted to give said plate lateral movements, as described.

27. In a coating machine, in combination with a carriage having center - grippers, a 105 tray, means for moving it into position under said carriage, means for causing said carriage to remove centers from said tray, and means operable after said centers have been moved from said tray adapted to de- 110 press said empty tray and move a full tray into its place.

28. In a coating machine, in combination with a carriage having center - grippers, a 115 tray, means for moving it into position under said carriage, means for causing said carriage to remove centers from said tray, and means operable after said centers have been moved from said tray adapted to de- 120 press said empty tray and move a full tray into its place, said depressing means comprising a cam, means connecting said cam with said carriage whereby it may be moved thereby, a lever operated by said cam and adapted to depress said tray, and means connected with said carriage adapted to draw 125 a full tray into position over said depressed tray, and means for maintaining said trays

thereafter in fixed relation to the center-removing position to the carriage.

29. In a coating machine, in combination with a carriage and a tray, means for giving said tray a horizontal movement comprising latches mounted to be moved horizontally by said carriage, each comprising a loop portion pivoted at one end thereof to a portion of said carriage, and means for holding said loop portion normally in horizontal position and a tongue pivoted in said loop portion at the other end thereof whereby when said loop portion is held in said horizontal position the free end of said tongue portion will hang in position to engage a movable part and move it when said carriage moves and when said loop portion is released from its horizontal position it will fly up and disengage said tongue from said movable part.

30. In combination, a stack of trays, stops, means for holding said stack against said stops, means for moving the top tray of said stack horizontally, a second set of stops and means for holding said horizontally-moved tray against said second set of stops, and means for depressing said holding means whereby it will release said horizontally-moved tray.

31. In a coating machine, a carrier, a series of individual center grippers, means for opening and releasing all of said grippers simultaneously, means for supporting and maintaining said center grippers in vertical

position in said carrier, and means for giving said carrier a vertical reciprocation.

32. In a coating machine, a series of individual center grippers, means for supporting them simultaneously in vertical position, and means for opening and closing them while in vertical position.

33. In a coating machine, a series of individual center grippers, means for supporting them in vertical position, means for closing them simultaneously, means for moving them horizontally while in vertical position, and means for lowering and lifting them vertically, means for rotating them while in lowered position, and means for opening them simultaneously to release the articles held.

34. In a coating machine, a series of individual center grippers, means for supporting them in vertical position, means for closing them, means for moving them horizontally while in vertical position, and means for lowering and lifting them vertically, means for rotating them while in lowered position, and means for opening them to release the articles held, in combination with a tank located under said grippers and adapted to receive said grippers when in lowered position.
